UNITED STATES PATENT OFFICE.

HENRY H. WAIT, OF CHICAGO, ILLINOIS, ASSIGNOR TO INTERNATIONAL SEPARATOR COMPANY, OF CHICAGO, ILLINOIS, A CORPORATION OF NEW JERSEY.

MAGNETIC ORE-SEPARATOR.

No. 832,826.

Specification of Letters Patent.

Patented Oct. 9, 1906.

Application filed March 20, 1905. Serial No. 251,073.

To all whom it may concern:

Be it known that I, HENRY H. WAIT, a citizen of the United States, residing at Chicago, in the county of Cook and State of Illinois, have invented a certain new and useful Improvement in Magnetic Ore-Separators, of which the following is a full, clear, concise, and exact description.

My invention relates to a magnetic separator, and has for its object to provide a machine which will be especially effective for the separation of ores of very low magnetic permeability, which separation requires the action of an extremely intense and concentrated magnetic field.

In magnetic attraction the movement of the permeable particle is always in the direction of converging lines of force—that is to say, the movement is toward the densest portion of the magnetic field. In accordance with my invention an extremely dense and concentrated field is formed by constructing the opposing magnetic pole-pieces between which the separating-field is established in the general form of two wedges facing each other at an angle, preferably at right angles, and the material to be separated is passed between these opposing magnetic cross-wedges, so that the more permeable particles are attracted to the surface of one of them, which therefore is made movable in order that the attracted material may be removed at a point distant from the place of separation.

A further feature of my invention consists of the provision of electromagnetic coils so placed as to oppose the passage of lines of force in certain paths to direct these lines of force into other paths from which they would otherwise tend to stray, the object being to produce a more concentrated magnetic field than would otherwise be possible.

My invention will be more particularly described and further features thereof pointed out in connection with the accompanying drawings, which illustrate a magnetic separator embodying said invention.

Figure 1 is a vertical sectional elevation of the ore-separator. Fig. 2 is a plan view thereof, the trough for feeding the ore being omitted for clearness and the auxiliary magnet-coils being shown in section. Fig. 3 is a

diagram of curves, illustrating the intensities of the magnetic field at different points and also illustrating in a dotted curve a variation in the distribution of the flux to produce a larger field of a common density at the particular place desired, as may be accomplished by the use of the auxiliary magnetizing-coils, hereinafter to be described. Fig. 4 is a detail sectional view on line 4-4 of Fig. 1, showing the relation of the auxiliary magnetizing-coils to the armature or revolving separating-carrier. Figs. 5, 6, and 7 are diagrams illustrating different forms of pole-pieces and the distribution of the magnetic flux secured in each case.

The same letters of reference indicate the same parts wherever they are shown.

Referring first to Figs. 1 and 2, the magnetic separator consists of a magnet-frame, preferably of hollow box form, with inwardly-projecting pole-pieces N and S and suitable magnetizing-windings thereon, creating a magnetic flux from one to the other—that is to say, the pole-pieces being of opposite polarity. Between the pole-pieces the armature B is rotatably mounted, the journals of the armature-shaft being at neutral points in the sides of the magnet-frame. The ore or material to be separated is arranged to be fed by means of a chute D between the face of the armature B and one of the pole-pieces N. In accordance with my invention the armature B and pole-piece N are formed so as to present ridges facing each other and extending in lines at an angle to each other. More particularly describing the machine illustrated, the end of the pole-piece N is beveled above and below, so that it is formed like a wedge, with its edge in a horizontal plane facing the armature B. The armature B, on the other hand, is beveled upon its two sides, so that a section of its edge opposite the pole-piece N would also be in the form of a wedge.

Thus we have the armature formed with a circumferential ridge facing a pole-piece, the end of which is formed to present a ridge at right angles with the plane of the armature-ridge—that is to say, parallel with the armature-axis. By this means it will be seen that the magnetic flux between the pole-piece N and the armature B will be highly concentrated upon the projecting circumferential

edge of said armature at the point opposite the pole-piece N. The direction of the magnetic lines of force will therefore be widely divergent from the extremity of the peripheral armature-ridge toward the opposing edge of the wedge-shaped pole-piece N at right angles. The feed-chute D is arranged to direct the material to be separated into the space between the circumferential ridge or edge of the armature and the opposing edge of the magnet-pole—that is, into the densest portion of the magnetic field. The edge of the pole-piece is preferably provided with a non-magnetic shield E to prevent the particles of material being treated from coming into a position where the influence of the pole-piece N is stronger than that of the armature B. F and G are divider-plates for separating the magnetic material, which tends to fall straight down away from said armature.

In order to concentrate the lines of force more effectually in the separating-gap between the armature and the pole-piece N, I preferably provide the auxiliary counter-magnetizing coils A A at the end of the pole-piece N and at either side thereof. The magnetizing-current sent through these coils should be in the direction to produce magnetic fluxes surrounding said coils in such a direction as to assist the flux between the pole-piece N and the armature B, where said pole-piece and armature most closely approach—that is, at the separating-gap—while opposing the leakage-flux from the extreme edges of said pole-piece N toward the armature. In other words, the location and magnetization of the auxiliary coils should be such as to prevent lines of force from straying from the outer edges of the pole-piece toward the armature and to direct such lines of force through the portion of the pole-piece which is directly opposite the edge of the separating-armature. This feature of my invention will be useful in many forms of magnetic separators, the idea being in general to provide auxiliary magnetizing-coils so wound and located as to prevent the undue dispersion of the magnetic flux and to concentrate such flux at the particular point where extreme density is required for effective magnetic separation. In Fig. 3 I have illustrated by means of curves the variation in the distribution of magnetism, which may be produced by such auxiliary counter-magnetizing coils. The curve H represents the magnetic density at the surface of the revolving armature, the density being taken at the intersection of a horizontal plane through the center of the armature, the surface L being developed into a straight line for the sake of simplicity. The actual form of the surface is indicated in the dotted lines. The intensity of the magnetic field at the surface is indicated in the diagram by the distance to the right from the surface line L.

Without the counter-magnetizing coils A A the density of the flux would be indicated in a general way by the curve H, and if we consider that the minimum density required for separation is represented by the distance of 70 the line K K from the line L it will be seen that the extent of surface having the required density is comparatively limited, being indicated by the distance X X upon the line K K. By the addition of the compensating windings A, as indicated in Figs. 1, 2, and 4, the magnetic flux at the ridges M M of the armature-surface more remote from the central ridge is decreased, while the flux from that portion of the surface nearest the central ridge is considerably increased. The result is not only a much higher density at the extreme edge of the circumferential ridge, but also a larger area of the surface represented by the distance Y Y upon the line K K 85 is permeated with a flux of the minimum separating strength. In other words, the amount of surface of the armature having a magnetic strength sufficient for an effective separation is increased, so that the capacity of the machine is increased.

Referring to Figs. 5, 6, and 7, the theory upon which the pole-piece and armature are formed to secure the required concentration of the magnetic field will be apparent. The force of adhesion is a function of the magnetic density. In the case of feebly magnetic substances it is necessary to have a very high magnetic density in order to get any considerable degree of attractive force. The simplest means of obtaining a very high magnetic density is by means of two pole-pieces of a general conical form, as indicated in Fig. 5. In order to use such magnetic densities in a continuously-acting commercial ore-separator, I have made one of the surfaces in the form of a revolving wheel or drum B, a cross-section of which at the periphery would be wedge-shaped. If the conical form for the magnetic pole which opposes the revolving wedge B is retained, as shown in Figs. 6 and 7, it will be seen that the lines of force diverge from the stationary pole—that is to say, the density will be higher at the surface of the stationary pole than it will be at the surface of the moving pole. This is undesirable, since it is intended that the magnetic particles should be attracted, but toward the stationary pole, not toward the revolving pole, so that the attracted material may be readily removed. In the form shown in Figs. 6 and 7 the density will not be as high on the surface of the armature as it is on the conical point, partly on account of the spreading of the lines of force toward the circumferential ridge of the armature and partly because the magnetic reluctance of the air-gap is decreased, thereby increasing the saturation of the pole-piece N, which was already working at a very high magnetic density. I therefore 130

prefer to make the pole-piece N in the form of a wedge, with its edge at right angles to the wedge-shaped surface of the armature, as shown in Figs. 1 and 2. The body of the 5 pole-piece is thus reinforced, thereby decreasing the saturation, so as to partially compensate for the extra saturation at the working point.

The armature is preferably laminated, so 10 as to avoid eddy-currents and permit the armature to be turned in the intense magnetic field with the minimum expenditure of energy.

The location of the armature between two 15 opposing pole-pieces of opposite polarity, as shown, not only tends to approximately balance the magnetic pull upon the armature, but also insures the establishment of a neutral point upon the surface of the armature 20 between the two poles, at which point even the more strongly-attracted material will be released.

The operation of the machine will be apparent from the foregoing description of its 25 structure. The material to be concentrated is fed into the feed-chute D and the armature is rotated in the direction of the arrow, the field-magnet being energized by electric current through the magnetizing-coils. As the 30 armature rotates the more permeable particles of ore will be attracted to its surface, the magnetic flux from the pole-piece N becoming denser as the surface of the armature is approached, and the pole-piece N being 35 further shielded by the non-magnetic plate E the more permeable particles adhering to the armature are carried around in the rotation thereof past the divider-plate F and are discharged on one side of said divider-plate, 40 while the non-magnetic particles continuing their course are discharged on the other side of the divider-plate G.

It will be apparent that my invention is capable of modification, and I do not desire 45 to be understood as limiting myself in all respects to the precise construction shown in the drawings; but

I claim—

1. In a magnetic separator, the combination 50 with a revolving magnet tapered from approximately its axial center to its periphery to form a wedge, of a magnet-pole tapering at its end, with the edge thereof in proximity to the edge of said revolving magnet and at an angle thereto, and means for feeding material to be separated into the gap between the edges of said opposed magnets.

2. In a magnetic separator, a revolving magnet comprising a shaft and a plurality of 60 disks mounted thereon, said disks being of gradually-decreasing circumferences on each side of the longitudinal center of the magnet, thereby forming a magnetic wedge, a wedge-shaped magnet-pole with its edge in proximity to the edge of said revolving magnet

and at an angle thereto, and means for feeding material to be separated into the gap between the edges of said magnets.

3. In a magnetic separator, the combination 70 with opposing pole-pieces of opposite polarity, of an armature mounted to rotate between said pole-pieces and tapered from approximately its axial center to its periphery to form a wedge, said armature being transversely laminated, one of said pole-pieces being tapered in a general wedge shape, with its edge at an angle to the edge of the armature-wedge, and means for feeding material to be separated into the gap 75 between the last-mentioned pole and said armature.

4. In a magnetic separator, the combination 80 with a revolving laminated carrier tapered from approximately its axial center to form a working surface of wedge-shaped 85 cross-section, of magnet pole-pieces of opposite polarity disposed on opposite sides of said carrier, one of said pole-pieces being constructed in a wedge shape, with its edge crossing the wedge-shaped surface of said 90 carrier approximately at right angles thereto, and means for feeding material to be separated into the gap between the edges of said opposed magnets.

5. In a magnetic separator, the combination 95 with opposing magnetic surfaces forming a working magnetic gap, of main magnetizing-coils for establishing the magnetic flux, and auxiliary counter-magnetizing coils adapted to provide a magnetomotive force in 100 opposition to the leakage-field, whereby the flux is concentrated in the working gap, substantially as set forth.

6. In a magnetic separator, the combination 105 with a revolving magnetic carrier and a magnet pole-piece adjacent thereto forming a working magnetic gap, of magnetizing-coils for establishing a flux through said gap, and auxiliary magnetizing-coils at the sides of 110 said gap establishing a magnetomotive force in opposition to the leakage-field at the sides of said gap, whereby the flux is concentrated and directed across said working gap, substantially as set forth.

7. In a magnetic separator, the combination 115 with a revolving laminated armature having a working surface of wedge-shaped cross-section, of magnet-poles of opposite polarity facing said armature, magnetizing-coils for establishing a flux between said poles 120 and said armature, auxiliary counter-magnetizing coils near the end of one of said pole-pieces at the sides thereof, said last-mentioned pole-piece being of wedge shape with its edge substantially at right angles to the plane of 125 the wedge-shaped armature, and means for passing material to be separated into contact with said armature, and through the gap between said armature and said last-mentioned pole-piece, substantially as set forth.

8. In a magnetic separator, the combination with opposing magnetic surfaces forming a working magnetic gap, of a magnetizing-coil at one side of said gap adapted to oppose the leakage-field and to direct the flux across said working gap, substantially as set forth

In witness whereof I hereunto subscribe my name this 13th day of March, A. D. 1905.
